CLAIM

The ornamental design for a bathroom stool as shown and described.

DESCRIPTION

FIG. 1 is a top, front perspective view of a bathroom stool showing our new design;

FIG. 2 is a bottom, rear perspective view thereof;

FIG. 3 is a front elevation view thereof;

FIG. 4 is a rear elevation view thereof;

FIG. 5 is a left-side elevation view thereof, a right-side elevation view being a mirror image thereof;

FIG. 6 is a top plan view thereof;

FIG. 7 is a bottom plan view thereof;

FIG. 8 is a cross-sectional view taken along the line 8-8 of FIG. 6;

FIG. 9 is a top, front perspective view of the bathroom stool shown in an alternate state with the cover opened;

FIG. 10 is a bottom, rear perspective view thereof;

FIG. 11 is a front elevation view thereof;

FIG. 12 is a rear elevation view thereof;

FIG. 13 is a left-side elevation view thereof, a right-side elevation view being a mirror image thereof;

FIG. 14 is a top plan view thereof; and,

FIG. 15 is a bottom plan view thereof.

1 Claim, 15 Drawing Sheets
